(57) CLAIM

The ornamental design for a plush tablet case, as shown and described.

DESCRIPTION

FIG. 1 is a front perspective view of an embodiment of a plush tablet case showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a first rear perspective view thereof; and,

FIG. 9 is a second rear perspective view thereof.

The broken lines shown in the drawings are included for the purpose of illustrating portions of the article that form no part of the claimed design.

The shading included in the drawings depicts texturing of plush features of the case.
